UNITED STATES PATENT OFFICE.

WINTHROP A. CLARK, OF STAMFORD, CONNECTICUT.

OIL-ENGINE.

1,084,131.

Specification of Letters Patent. Patented Jan. 13, 1914.

Application filed December 5, 1911. Serial No. 664,100.

To all whom it may concern:

Be it known that I, WINTHROP A. CLARK, of Stamford, in the county of Fairfield and State of Connecticut, have invented certain 5 new and useful Improvements in Oil-Engines, of which the following is a specification.

The present invention relates to internal combustion motors of the type in which oil 10 is used as the fuel, and in which such fuel is introduced directly into the combustion chamber of the motor without previous admixture with air.

More particularly the invention is concerned with a means for atomizing the oil fuel and preventing deposit of hard carbon 15 on the interior of the combustion chamber.

With this object in view the invention consists mainly in the provision of a cooled surface 20 against which the oil when first admitted is caused to impinge and by which it is broken up into small particles and distributed throughout the combustion chamber, in combination with means for injecting the oil, and means for igniting the same.

An embodiment of means for carrying my invention into effect is illustrated in the accompanying drawings and described in the following specification.

20 In the drawings, Figure 1 represents a longitudinal sectional view of the combustion chamber of an internal combustion motor, to which my invention is applied. Fig. 2 is a side elevation of the same as seen 25 from the right of Fig. 1. Fig. 3 is a cross section on line 3—3 of Fig. 1.

In order that the purpose of my invention may be more readily understood I will describe briefly a common and well-known 30 type of oil engine and the objectionable condition which occurs in the use of such engine, and which it is the purpose of my invention to overcome, before proceeding to a detailed description of the improvement in which my 35 invention resides. In certain types of engine using comparatively non-volatile oil as fuel and injecting such oil directly into the engine cylinder, the ignition is effected by forcing the oil in a stream against a hot surface. The stream is broken up into fine 40 particles by impact against the surface, which particles are first vaporized and then ignited by the heat retained in the hot surface and in adjoining parts of the cylinder head. It has been found that there is a 45 tendency in such engines for the oil to

carbonize on the hot surface, with depositions of solid carbon in the shape of a ring or crater surrounding the point of impingement of the fuel stream, which is productive 50 of certain very obnoxious effects. The crater is constantly being built up while the engine is in use, and after a time extends so far from the impingement surface as to surround and confine the film of oil, preventing the particles from being projected from its edge and from mixing thoroughly with the air already compressed in the combustion chamber. In this way mixing of the oil vapor with air which is necessary to 55 secure complete combustion, is retarded, the vapor and air are not properly mixed, and the oil is not thoroughly consumed. Another objectionable result is that the material in the crater becomes incandescent and 60 causes premature ignition of the oil immediately adjacent to it, resulting in incomplete combustion with more and more rapid deposit of solid material on the crater. The manner in which I avoid this objectionable 65 result, stated in the briefest manner, is by providing a cool surface for impingement of the oil.

Referring to Fig. 1 which shows an embodiment of my invention in detail, 1 represents the cylinder of an internal combustion engine and 2 represents the head thereof enclosing a combustion space 3. This head is secured to the body of the cylinder in any suitable way, as by bolts 4. 5 represents the nozzle through which the fuel is injected and 6 represents the impingement surface. This surface is air insulated from the head 2 and is maintained constantly at a temperature enough lower than the dissociation temperature of the oil to prevent the formation of deposit of the character above referred to. For the purpose of maintaining this temperature I provide means for circulating a cooling liquid, ordinarily water, in thermal contact with the surface. Accordingly the impingement surface is made as the end wall of a hollow plug or tube 7 which passes through the end wall of the cylinder head at or near the center thereof, 80 as shown clearly in Fig. 1. This plug, which may also be called an impingement member, is preferably secured by an integral flange 8 within the cylinder head and a nut 9 screwed upon it outside of the head, such 85 flange and nut gripping the head between them. Cooling water is circulated through

the impingement member, being delivered at a point close to the surface or wall 6 by an inlet tube 10 and passing away through the space 11 in the plug outside such tube. 5 A coupling 12 is fastened upon the outer end of the plug and has an inlet branch to which the cooling water is conducted by a pipe 13 and through which the induction pipe 10 extends. To another branch of the 10 coupling is coupled a pipe 14 for carrying away the cooling water.

The fuel nozzle 5 passes through the side of the cylinder head and is also preferably water-cooled. Such nozzle which is fully 15 described and claimed in Letters Patent No. 1,031,422, granted to me July 2, 1912, is conveniently made as a casting having a central passage 15 for the fuel and passages 16 and 17 on each side of the fuel passage 20 for the cooling water. These water passages are connected at the end of the nozzle by a transverse channel 18. For convenience in casting and finishing the nozzle it is made with the oil channel open at both ends and 25 with an opening in the outer wall in line with the oil channel. When finished this opening is closed by a plug 19 and the adjacent end of the oil channel is closed by a plug 20. A pipe 21 conducts oil to the channel 15 and is connected thereto by a nipple 22 and coupling 23. A pipe 24 for supplying cooling water to the channel 16 of the nozzle is connected at one side of the nozzle, and an eduction pipe is connected to the opposite side of the nozzle in communication with the channel 17. The eduction pipe may 30 conveniently be the pipe 18 which conducts the cooling water to the impingement plug or member 7. In this way the same cooling 35 water is caused to flow through both the nozzle and the impingement member. In the side of the fuel channel nearest the impingement surface is an opening which is closed by a screw plug 25 having a passage 40 directed toward the impingement surface and terminating in a restricted orifice 26 which governs the size of the ejected jet. Preferably the jet orifice is located in the axis of the cylinder and the impingement 45 surface is in a plane perpendicular to the axis, so that the jet is caused to strike squarely against the impingement surface and be dispersed equally in all directions throughout the combustion chamber.

50 Surrounding the impingement member is a ring 27 which is set somewhat back from, or above, the plane of the impingement surface and is insulated by an air space therefrom. This ring is hung from the head 2 55 in such a manner as to be practically insulated therefrom. There may also be suspended near the side walls of the head a larger ring 28 which is not an absolute necessity, but may be a useful adjunct to the 60 engine.

An ignition tube 29 is secured in the head with its interior communicating with the combustion chamber. Finally a hood 30 is placed over the head in such a manner as to inclose a space adjacent to the end wall 70 of the head. This hood has an opening 31 near the ignition tube 29 and a second opening 32 at the opposite side. The purpose of the hood is to confine the flame of a torch used for heating the ignition tube and cylinder head in starting the engine when cold, and also to maintain the temperature of the head at a high degree after the engine is running by forming an air chamber around the hood, the hood preventing currents of 75 air from cooling the head itself.

In starting the engine the head and ignition tube are first heated by means of a torch, then a charge of oil is injected, and the piston is moved so as to draw a charge 80 of air into the cylinder and to compress the air in the cylinder head. Preferably the stroke is long enough to carry the piston nearly up to the cylinder head so that the entire charge is compressed in the combustion space 3. Some of the oil is carried by 85 the air into the heated tube 29, which, with the aid of the heat of compression, causes the first charges to be ignited. After a few explosions have occurred the rings 27 and 90 28 become red hot and the ignition tube and cylinder head are allowed to cool off. The purpose of the ring 27 is to retain a sufficient degree of heat to ignite the atomized and vaporized oil scattered from the impingement surface 6, while the ring 28 is intended to retain heat for heating the compressed charges of air. The engine will run 95 satisfactorily, however, without the ring 28, consequently the same is not an indispensable part of my invention and may be omitted without departing from the spirit of the invention.

A sufficiently rapid circulation of cooling water is maintained in the impingement plug to keep the surface 6 thereof at a temperature lower than that at which the oil is broken up into its elements. Thus the oil adhering to the plug around the point of contact of the steam is not burned or destroyed, but is thrown out by the impact of the steam in all directions without restriction. The coating of oil which remains on the surface between charges is not burned, but remains in liquid condition and is forced 100 away by the succeeding charge. As soon as the separated particles pass beyond the cooled impingement surface they come into range of the heat radiating from the ring 27 and to some extent into contact with the ring, being thereby vaporized and ignited. If the surface 6 were not cooled as described, the oil striking upon and adhering to it 105 would be destroyed, with deposition of a crust which would in time form a crater, 110 115 120 125 130

with the objectionable results outlined at the beginning of this specification.

It is to be understood that I do not limit the broader aspects of my invention to the particular details of construction and arrangement of parts here shown and illustrated, as the invention may be embodied in many other forms and may be employed in connection with engines of widely varying types without departing from the spirit and scope thereof.

I claim,—

1. In an internal combustion motor having a combustion space, means for injecting liquid fuel into said combustion space, a member projecting into said combustion space from the wall thereof upon which the fuel impinges, means for abstracting heat from said member and maintaining its temperature at a relatively low point, and an incandescent igniting member surrounding said first-named member.

2. In an internal combustion motor having a combustion space, means for injecting liquid fuel into said combustion space, a member projecting into said combustion space from the wall thereof upon which the fuel impinges and air insulated from said wall, means for abstracting heat from said member and maintaining its temperature at a relatively low point and an incandescent igniting member surrounding said first-named member.

3. In an internal combustion engine having a combustion chamber, the combination of an impingement member extending into the combustion chamber, means for cooling such impingement member, injecting means arranged to throw a jet of oil against said member, and a heat-retaining body adjacent to said impingement member and air insulated from the chamber walls for igniting the fuel.

4. In an internal combustion engine hav-

ing a combustion chamber, the combination of an impingement member extending into the combustion chamber and insulated from the walls thereof, means for cooling such impingement member, injecting means arranged to throw a jet of oil against said member, and a heat-retaining body adjacent to said impingement member and also insulated from the chamber walls for igniting the fuel.

5. In an internal combustion motor having a combustion space, the combination with a jacketed fuel nozzle projecting into the combustion space of the engine, of a hollow impingement member opposed to the nozzle outlet, and means for circulating a cooling fluid in series through the nozzle jacket and the impingement member.

6. In an engine of the character described, an impingement plug extending into the combustion chamber of the engine and having a substantially plane end surface, means for continually abstracting heat from said plug, a nozzle extending into the combustion chamber and arranged to discharge against such end surface, and a heat-retaining body surrounding said plug and insulated therefrom.

7. In an internal combustion engine, a recessed cylinder head inclosing a combustion chamber, a hollow plug projecting through the end of the head, means for circulating water through said plug, a heat-retaining ring suspended from the head and surrounding the plug, and a second heat-retaining ring adjacent to the side walls of the cylinder head for imparting heat to the air compressed in the combustion chamber.

In testimony whereof I have affixed my signature, in presence of two witnesses.

WINTHROP A. CLARK.
